DARKROOM LIGHT FIXTURE

Harold R. Benson, Lombard, Ill., assignor to The Nuarc
Company, Chicago, Ill., a corporation of Illinois

Filed Nov. 29, 1963, Ser. No. 77,611

Term of patent 14 years

(Cl. D48—23)

FIG. 1

FIG. 2

FIG. 3

FIG. 4

FIG. 5

FIG. 1 is a perspective view of a darkroom light fixture embodying my new design;

FIG. 2 is a top plan view thereof;

FIG. 3 is an end elevational view thereof;

FIG. 4 is a bottom plan view thereof; and

FIG. 5 is a side elevational view thereof.

The essential features of the design reside in the portions shown in full lines.

I claim:

The ornamental design for a darkroom light fixture, substantially as shown and described.
